UNITED STATES PATENT OFFICE.

CHARLES DAVID BONSALL, OF PITTSBURGH, PENNSYLVANIA, ASSIGNOR TO P. H. MURPHY COMPANY, OF NEW KENSINGTON, PENNSYLVANIA, A CORPORATION OF PENNSYLVANIA.

CAR ROOF.

Application filed March 1, 1926. Serial No. 91,291.

My invention relates to that type of flexible outside metal car roof, wherein the roofing sheets extend from eaves to ridge of the car and are arranged for sluing or oscillatory movement thereon in accommodating themselves to the distortion of the car-body.

The principal object of the present invention is an improved seam construction that will secure an independent oscillatory or sluing movement of the roof sheets around points located in the region of the middle of their adjacent margins whenever there is movement of said sheets. Other objects are simplicity and cheapness of construction, compactness and economy of design and ease of assembly.

The invention consists principally in a pivot member for the roof sheets to turn on and in the manner of securing said pivot member in position; and the invention further consists in the parts and in the combinations and arrangements of parts hereinafter described and claimed.

In the accompanying drawing, which forms part of the specification and wherein like symbols refer to like parts wherever they occur,

Fig. 1 is a plan view of a flexible outside metal car roof embodying my invention, parts being shown broken away to more clearly illustrate the invention;

Fig. 2 is an enlarged vertical cross-section through the ridge portion of the roof midway of the transverse seams thereof on the line 2-2 in Fig. 1;

Fig. 3 is a similar cross-section taken adjacent to one of the transverse seams on the line 3-3 in Fig. 1;

Fig. 4 is a vertical cross-section through one of said transverse seams on the line 4-4 in Fig. 1;

Fig. 5 is a vertical section through the eaves portion of the car on the line 5-5 in Fig. 1; and

Fig. 6 is a perspective view of one of the pivot pieces upon which the sheets rock or roll in accommodating themselves to the distortions of the car-body.

Referring to the accompanying drawing, my invention is shown applied to an ordinary type of car, whose roof sheathing boards 7 are supported at the eaves and ridge of the car on side plates 8 and ridge pole 9 thereof. Metal roof sheets 10 extend transversely of the car from eaves to ridge

thereof and are provided at their ridge ends with upstanding seam flanges 11 of substantially S-shaped section, forming outwardly opening grooves 12 which extend longitudinally of the ridge margins of the sheets from end to end thereof. The side margins of the sheets are provided with upstanding inwardly hooked side seam flanges 13; and the eaves ends of the sheets are provided with doubled-under flanges 14.

The roof sheets 10 are arranged in pairs on opposite sides of the ridge of the car, the two sheets of each pair being disposed end to end crosswise of the car and spaced apart from each other on opposite sides of the ridge and from adjacent pairs along their side margins. Mullions or battens 31 are secured to the roof sheeting between the side margins of the sheets and are of less width than the spaces there between, thereby permitting a limited angular adjustment of the sheets between battens. The roof sheets are held down on the car at the eaves by hooking their doubled-under flanges 14 into the doubled-back portions 15^a of angle flashing strips 15 that are nailed or otherwise rigidly secured to the eaves portions of the roof.

The side margins of adjacent roof sheets, together with the mullions located therebetween, are covered by inverted channel-shaped transverse seam covers 16 whose side-walls interlock with the side seam flanges 13 of adjacent roof sheets. The transverse seam covers extend from ridge to eaves of the car and are held down at the eaves preferably by turning their eaves ends under the doubled-back portions 15^a of the eaves flashing strips 15. The transverse seam covers 16 are secured in place at the ridge by the usual pan-shaped four-way corner caps 17. These corner caps are secured in position by vertical bolts 18 that secure the running board saddles 19 in position.

The spaced S-shaped ridge flanges 11 of adjacent roof sheets are straddled by inverted channel-shaped ridge seam covers 20, whose adjacent ends are covered by the ridge corner caps 17 and are held in proper alignment thereby. The ridge seam caps 20 are provided with outstanding base flanges 20^a, which rest on the body portions of the sheets inside the S-shaped ridge flanges 11 thereof, and said ridge seam caps are made wider at their ends than at their middle, so as to limit their contact with said ridge seam

flanges to the narrow middle portions thereof and thus permit a limited angular adjustment of said ridge seam flanges within said ridge seam caps.

Sheet metal pivot members or pieces 21 are provided for spacing the sheets apart at the ridge and for securing a limited pivotal or sluing movement of the sheets about points located in the region of the middle of their ridge ends. The pivot members extend longitudinally of the car at the ridge between the spaced ridge flanges 11 of the sheets and have rebent or doubled-back side marginal portions forming hollow ribs 22 adapted to fit within the outwardly opening grooves 12 of the ridge flanges 11 of the sheets. The pivot pieces 21 are of a maximum width midway of their length and gradually decrease in width toward their ends, whereby the contact between the sides of the pivot pieces and the bottoms of the grooves in the ridge flanges of the sheets is limited to points located midway of the ridge ends of said sheets. By this arrangement, the sheets are forced to rock or roll upon the wide middle portions of the pivot pieces or the narrow middle portions of the ridge seam covers whenever there is movement of the sheets. The tapered body portions of the pivot pieces extend the full width of the sheets between mullions and have upwardly offset end portions or flanges 23 that overlap the mullions and are perforated to receive the vertical bolts 18 which secure the corner caps 17 and running board saddles 19 in position. The overlapped flanges 23 of adjacent pivot pieces, together with the adjacent ends of the transverse seam caps 16 and ridge seam caps 20 are covered by the four-way corner caps 17, thereby securing a substantially weather-proof joint at this portion of the roof.

By the arrangement described, the pivot pieces and the ridge seam covers have line contact with the outer and inner sides of the ridge flanges of the sheets midway of their ridge ends and are spaced therefrom at their ridge corners, whereby the sheets are permitted to accommodate themselves to distortion of the car frame by pivoting or sluing about the contacting portions of said pivot members and said ridge seam cover. It is noted as an important advantage of my invention that it utilizes the saddle bolts as a means for securing the pivot pieces in place and thereby saves the cost of separate fastening members for said pivot pieces and facilitates assembly of the latter on the car.

Obviously, the hereinbefore described arrangement admits of considerable modification without departing from the invention; therefore I do not wish to be limited to the precise arrangement shown and described. For instance, the pivot pieces and the ridge seam covers may be given the necessary

taper by means of reversely curved surfaces.

What I claim is:

1. A flexible car roof comprising movably mounted roof sheets spaced apart 70 along their adjacent margins and having outwardly opening grooves extending along said margins, a pivot member secured to the car and engaging the adjacent marginal grooves of said sheets and a seam cover secured to the car and covering said pivot member and the grooved marginal portions of said sheets, said pivot member being normally in contact with the bottoms of said grooves for a portion of their length only. 80

2. A flexible car roof comprising movably mounted roof sheets spaced apart along their adjacent margins and having outwardly opening grooves extending along said margins, a pivot member secured to the car 85 between the adjacent margins of said sheets and engaging the grooves therein, and a seam cover secured to the car and covering said pivot member and the adjacent marginal portions of said sheets, said pivot member being normally in contact with the bottoms of said grooves midway of their length only. 90

3. A flexible car roof comprising movably mounted roof sheets spaced apart along 95 their adjacent margins and having outwardly opening grooves extending along said margins, a pivot member secured to the car and extending into the adjacent marginal grooves of said sheets, and a seam cover secured to the car and covering the said pivot member and the adjacent marginal portions of said sheets, said pivot member being normally in contact with the bottoms of said grooves midway of their length and spaced 100 therefrom at their ends, the securing means for said seam cover serving also as the securing means for said pivot member. 105

4. A flexible car roof comprising movably mounted roof sheets spaced apart along 110 their adjacent margins and having upstanding flanges along said margins that are provided with outwardly opening longitudinal grooves, a pivot member secured to the car and engaging the marginal grooves of adjacent sheets, and a seam cover secured to the car and covering said pivot member and the grooved flanges of said sheets, said pivot member being normally in contact with the bottoms of the grooves in the adjacent marginal flanges of said sheets for a portion of 115 their length only, and said seam cover being normally in contact with the sides of said adjacent seam flanges for a portion of their length only. 120

5. A flexible car roof comprising movably mounted roof sheets spaced apart along adjacent margins and having upstanding flanges along said margins that are provided with outwardly opening longitudinal 125 grooves, a pivot member secured to the car and engaging the marginal grooves of adjacent sheets, and a seam cover secured to the car and covering said pivot member and the grooved flanges of said sheets for a portion of their length only, and said seam cover being normally in contact with the sides of said adjacent seam flanges for a portion of their length only. 130

grooves, a pivot member secured to the car and engaging the adjacent marginal grooves of said sheets, and a seam cover secured to the car and covering said pivot member and the grooved upstanding marginal flanges of said sheets, said pivot member being widest and said seam cover being narrowest midway of the length of said adjacent flanges, whereby the contact between the grooves in 5 the sheet flanges and the sides of said pivot member and the sides of said sheet flanges and said seam cover is normally limited to the middle portions of the adjacent margins of said sheets.

15. 6. A flexible car roof comprising a sub-structure having transversely arranged battens and roof sheets arranged on each side of the ridge between said battens, said roof sheets being formed with upstanding ridge flanges having outwardly opening grooves extending lengthwise thereof, side seam covers covering said battens and the adjacent side margins of said roof sheets, ridge seam covers covering the spaced ridge flanges of adjacent sheets, corner caps covering the ridge portions of said side seam covers and the adjacent ends of said ridge seam covers, and a pivot member secured to the car and extending from batten to batten between the ridge flanges of adjacent sheets and engaging the grooves therein, said pivot member and said ridge seam cover being shaped to limit the contact between the bottoms of said grooves and said pivot member and the sides of said ridge seam covers and said ridge seam flanges to the middle portions of the ridge ends of said sheets.

7. A flexible car roof comprising a sub-structure having transversely arranged battens and roof sheets arranged on each side of the ridge between said battens, said roof sheets being formed with upstanding ridge flanges having outwardly opening grooves extending lengthwise thereof, side seam covers covering said battens and the adjacent side margins of said roof sheets, ridge seam covers covering the spaced ridge flanges of adjacent sheets, corner caps covering the ridge portions of said side seam covers and the adjacent ends of said ridge seam covers, and pivot members secured to the car and extending from batten to batten between the ridge flanges of adjacent sheets and engaging the grooves therein, said pivot pieces being wider at their middle than at

their ends and said ridge seam covers being wider at their ends than at their middle, whereby the contact between said pivot members and the bottoms of said grooves 60 and the side walls of said cap ridge seam covers and said flanges is limited to the middle portion of the ridge ends of said sheets.

8. A flexible car roof comprising a sub-structure having transversely arranged battens and roof sheets arranged on each side of the ridge between said battens, said roof sheets being formed with upstanding ridge flanges having outwardly opening grooves 65 extending lengthwise thereof, side seam covers covering said battens in the adjacent side margins of said roof sheets, ridge seam covers covering the spaced ridge flanges of adjacent sheets, corner caps covering the adjacent ends of said side seam covers and ridge seam covers, means for securing said corner caps to the car, and pivot members extending from batten to batten between the ridge flanges of adjacent sheets and engaging the grooves therein, said pivot members having end portions that overlap said battens and are secured thereto by the securing means for said corner caps, said pivot members being wider at their middle than 70 at their ends and said ridge seam covers being wider at their ends than at their middle.

9. A pivot member for flexible car roofs, said member comprising an elongated body 90 adapted to be secured to the car between the spaced margins of adjacent roof sheets, of greater width at its middle than at its ends, whereby said body is normally adapted for engagement with said sheets at its middle 95 only.

10. A pivot member for flexible car roofs, said member comprising an elongated body of greater width at its middle than at its ends and end portions that are perforated 100 to receive fastening members.

11. A sheet metal pivot member for flexible car roofs, said member comprising an elongated body portion having doubled-back flanges along its side margins and offset end portions that are perforated to receive fastening members, said body portion being wider at its middle than at its ends.

Signed at New Kensington, Pa., this 20th day of February, 1926.

CHARLES DAVID BONSALL.
